UNITED STATES PATENT OFFICE

ERNEST THOMAS FISK, OF SYDNEY, NEW SOUTH WALES, AUSTRALIA

SOUND SUPPRESSING VENTILATOR FITTING FOR WINDOWS

Application filed March 19, 1930, Serial No. 437,178, and in Australia July 27, 1927.

The object of this invention is to provide means for screening casement windows when open against the entry of external noises.

The invention is illustrated in the accompanying drawing, in which:

Fig. 1 is a perspective view showing a vertical sound proof panel hinged to the free vertical edge of an open casement sash and a horizontally disposed sound proof panel structurally adapted to protect the space between the lower edge of the window aperture and the lower edge of the vertical sound proof panel.

Fig. 2 is a vertical transverse section of the arrangement shown in Fig. 1.

16 and 17 are the casement sashes, 12a the vertical sound proof panel and 13 the horizontally disposed sound proof panel. The panel 12a is hinged at 24a the sash 16, and the panel 13 is hinged at 25 to the lower edge of the window aperture. The lower panel 13 may be constructed as a hollow cell as shown in Fig. 2 or it may be solid. It may be of any suitable opaque, transparent or translucent material, or it may be made of sound absorbent material, or lined with sound absorbent material. It is preferably provided with ventilating apertures 13a through which ventilating air passes freely and when constructed as a hollow cell sound waves are absorbed in the enclosed air space.

The panel 12a is transparent or translucent to facilitate the passage of light. The sash 16 in combination with the panels 12a and 13 when placed in the position shown in the drawing constitutes an enclosure which promotes ventilation and allows the passage of air out of and into the apartment while minimizing by reflection and absorption entry of sound waves from outside the apartment.

The vertical sound proof panel 12a is hinged at 24a to the casement sash 16. The sound proof panel 13 is hinged to the lower edge of the window aperture and extends outward so that it fills the space between the lower edges of the sash 16 and the panel 12a.

The method of treating double casement windows may be varied by hinging one vertical sound proof panel to each of the case-

ment sashes and making provision for the free edges of the two vertical panels to meet when the sashes are opened and the sound proof panels are in position. The outward extending panel in this case extends from the lower edge of the window aperture to the lower edges of the two vertical panels.

What I claim as my invention and desire to secure by Letters Patent is:—

1. A sound suppressing ventilating attachment for casement windows comprising a casement sash and an auxiliary panel structurally adapted to form two sides of a triangular hopper like structure, the other side and the top of which are left open and a panel extending outward from the lower edge of the window aperture constituting the bottom of said hopper like structure. 60

2. A sound suppressing ventilating attachment for a casement window, comprising a casement sash, an auxiliary panel hingedly attached to said sash, said casement sash and said auxiliary panel together constituting two sides of a hopper-like structure, the other side and the top of which are left open and a panel extending outward from the lower edge of the window aperture constituting the bottom of said hopper-like structure. 70

In testimony whereof I affix my signature.
